UNITED STATES PATENT OFFICE.

BENJAMIN S. BERNHARD, OF BOSTON, MASSACHUSETTS.

DOOR CLOSING AND CHECKING MECHANISM.

Application filed July 24, 1922. Serial No. 576,927.

To all whom it may concern:

Be it known that I, BENJAMIN S. BERNHARD, a citizen of the United States, and resident of Boston, in the county of Suffolk and 5 State of Massachusetts, have invented a new and useful Door Closing and Checking Mechanism, of which the following is a specification.

One object of my invention is to provide 10 simple but efficient mechanism for preventing undesired closing of a door or the like, as, for example, closing by the wind.

Another object is to provide guiding 15 means for a flexible member which may be used for desired closing of the door.

Other objects will be pointed out below.

A feature of my invention is the provision 20 of means, separate from the closing means, for preventing undesired closing which is likely to result in noise, and in breaking of 25 glass, if the door carries glass and in the preferred form a flexible member is used to connect the door and support and the moving parts of the device are preferably in- 25 visible when the door is closed.

Other features will be pointed out below. In the drawings.

Figure 1 is a plan, partly in section, of a 30 device embodying my invention; Figure 2 is a front elevation of the same; Figure 3 is a plan, partly in section, but showing the door closed.

Figure 4 is a section on line 4—4 of Figure 2;

Figure 5 is a section on line 5—5 of Figure 1;

Figure 6 is a section on line 6—6 of Figure 5;

Figure 7 is an elevation, partly in section, 40 showing the door closed;

Figure 8 is an end elevation of the anchorage;

Figure 9 is a plan showing the door partly closed;

Figure 10 is a detail showing a modified form of projecting member, described below; and

Figure 11 is an end elevation of the parts 50 mounted in the door and looking from the left in Figure 2.

In the drawings I show a right-handed hinged door but my invention is applicable to doors or the like which have left-handed mountings or other mountings than hinged.

55 The door frame A is recessed to receive an

anchoring member A', the outer portion of which is flush with the frame and is held by screws a and a' and has an opening a² leading to recess a³ suitably formed for universal swinging connection with member a⁴ which has connection with flexible member A² which is preferably a metal strap but might be of any suitable shape or material, the preferred connection being made by passing the end of member A² through opening a⁵ in member a⁴ and then attaching a holding element such as rivet a⁶ seated in recess a⁷.

Member a⁴ is mounted to rotate and is preferably a ball and plate A³ is held to member A' by screws A⁴ so that said plate and member A' form a socket which substantially prevents lateral movement of member a⁴, that is, prevents all movement of member a⁴ except movement of rotation, one purpose being to protect the member a⁴ from foreign matter and another purpose being to improve the cooperative action of member a⁴ and member A² and I preferably solder rivet a⁶ in recess a⁷. 80

Embedded in the door B is a cylindrical casing B' having a plate portion b, the outer portion of which is flush with the edge of the door, said plate portion being held in position by screws b', and having a perforation b² to permit passage of member A². Bushing b³ carries thimble b⁴ which furnishes one abutment for spring B² and said thimble, and consequently the spring may be adjusted by screw b⁵. The other abutment of the spring is the piston B⁶ provided with rack B⁷ engaging pinion B⁸ on shaft B⁹, to which is pinned flanged drum B¹⁰, around which is wound the end of member A², said end being connected to said drum at B¹¹. The piston is provided with a strengthening web b¹² and with ball valves of a well-known type and conduit B¹³ leads from one end of the casing nearly to the other end, said conduit being controlled by valve B¹⁴, the head of which is in threaded engagement with a threaded recess in the casing. 85 90 95 100 105

The casing B' has a boss b¹⁵ having a central opening large enough to permit passage therethrough of bearing member b¹⁶ which may be then threaded into place, after which the shaft B⁹ with its pinion is put in place through said opening and then bearing member b¹⁵ is put in place, after 110

which the hub *d* of gear *D* is inserted in the bore of drum *B'* and then said hub and drum are pinned to shaft *B⁶*.

- The casing is preferably completely filled 5 with suitable fluid and as the door is moved from its closed position the member *a'* swings and the flexible member *A²* is unwound, rotating the drum and consequently the pinion and moves the piston to 10 the left as in Figure 4, compressing the spring and permitting most of the fluid to flow past the balls of the ball valves and some through conduit *B⁹*. When the door is released the spring acts to return the piston 15 to the original position and thereupon the fluid passes through conduit *B⁹* but can not return past the balls and the drum actuated by the rack and pinion winds up member *A²* and thereby closes the door, the 20 checking action being caused by the fluid passing through conduit *B⁹* and controlled by valve *B¹⁰* and when the door is closed as shown in Figure 6 there will be absolutely 25 no portion of the device visible from either side of the door.

In installing my device, in case, for example, casing *B'* is to be mounted in the door, I draw strap *A²* out and hold it in any suitable way. The casing is then inserted 30 in the door and held in place by screws *b'* and the anchorage *A'* is inserted in the frame and held by screws *a* and *a'*.

As a convenient way of putting strap *A²* in place I provide slot *b¹⁰* in plate *b* through 35 which member *A²* may be lowered into opening *b²*.

In order to prevent undesired closing of the door as, for example by a strong wind 40 I provide a rigid rod *E* having threaded connection with rack *E'* and preferably I provide a socket *e* in rod *E* to receive coiled spring *e'* to act as a lock for holding members *E* and *E'* in the desired position of adjustment. The teeth of rack *E'* engage the 45 teeth of gear *D* and the checking mechanism therefore controls the movement of members *E* and *E'*, member *E* moving in bearing *e²* and member *E'* moving in bearing *e⁹*. When the door or the like is opened by hand 50 the gear *D* acts to force member *E* outwardly through opening *e²* and when the hand is removed the gear *D* moves in the opposite direction and returns the member *E* to the position shown in Figure 3. If 55 however a strong wind or other undesired force should close the door more rapidly than is desired the member *E* will engage member *A'* or other portion of the support and will prevent complete closing until 60 member *E* has been fully withdrawn, it being understood that the rearward movement of member *E* is so timed that member *E* will cease to project at the instant of complete closing of the door. If the door should 65 become warped or for any reason there is

undue space between the door and support when the door is closed the member *E* may be adjusted with relation to member *E'* so that the member *E* will be just free of engagement with the support when the closing is complete. 70

In Figure 10 I show a modification in which the rod *E²* has a reduced portion *e⁴* frictionally engaging one end of coiled spring *e⁵*, the other end frictionally engaging reduced portion *e⁶* of rod *E²*, the purpose of this form being to absorb shock due to undesired closing. 75

Guides *F* *F'* are provided to prevent the strap *A²* from coming in contact with the 80 wood of the door or the like or with the wood of the support in case the checking mechanism is mounted in the support, and these guides are extended in the form shown at *G* and *G'* to keep the flexible member *A²* 85 from riding above or below the flanges of the drum.

For purposes of clearness I have disclosed 90 in this application a number of features disclosed in my application Serial No. 551,902 90 but the features claimable in said application are not claimed herein.

What I claim is:

1. A device of the character described comprising a door or the like; a support 95 therefor; means to close the door including a flexible element which extends from the door to the support; means to check the closing action of the closing means; and means additional to said checking means to stop undesired closing of the door. 100

2. A device of the character described comprising a door or the like; a support therefor; means to close the door including 105 a flexible element which extends from the door to the support; means to check the closing action of the closing means; and means including a longitudinally movable rod to stop undesired closing of the door.

3. A device of the character described comprising a door or the like; a support 110 therefor; means to close the door including a flexible element which extends from the door to the support; means to check the closing action of the closing means; and means additional to said checking means and including a longitudinally movable rod to stop undesired closing of the door. 115

4. A device of the character described comprising a door or the like; a support 120 therefor; means to close the door including a flexible element which extends from the door to the support; means to check the closing action of the closing means; and rigid means to stop undesired closing of the door. 125

5. A device of the character described comprising a door or the like; a support therefor; means to close the door including a flexible element which extends from the door to the support; means to check the clos- 130

ing action of the closing means; and means controlled by said checking means to stop undesired closing of the door.

6. A device of the character described comprising a door or the like; a support therefor; means to close the door which includes a flexible element which extends from the door to the support; means to check the closing action of the closing means; and means including a longitudinally movable rod controlled by said checking means to stop undesired closing of the door.

7. A device of the character described comprising a door member; a supporting member therefor; an anchorage embedded in one of said members; operating mechanism embedded in the other of said members; means including a flexible member connecting the anchorage and said operating mechanism to close the door; means to check the closing action; and a rod mounted on the member carrying the operating mechanism and movable longitudinally to project beyond that member to engage the other member to prevent undesired closing of the door, said rod being controlled by the checking means.

8. A device of the character described comprising a door member; a supporting member therefor; an anchorage embedded in one of said members; operating mechanism embedded in the other of said members; means including a flexible member connecting the anchorage and said operating mechanism to close the door; means to check the closing action; and an adjustable rod mounted on the member carrying the operating mechanism and movable longitudinally to project beyond that member to prevent undesired closing of the door, said rod being controlled by the checking means.

9. A device of the character described comprising a door; a support therefor; operating mechanism including a spring and a rotary element; a flexible member operatively connecting the door and support and extending from one of them to the other and extending operatively into one of them to engage said rotary element; and means with in that member into which the flexible member operatively extends to guide said flexible member with relation to said rotary element.

10. A device of the character described comprising a door; a support therefor; operating mechanism including a spring and a rotary element; a flexible member operatively connecting the door and support and extending from one of them to the other and having winding connection with said rotary element; and means to guide the flexible member with relation to said rotary element.

11. A device of the character described comprising a door member; a supporting member therefor; an anchorage embedded

in one of said members; operating mechanism embedded in the other of said members; means including a flexible member connecting the anchorage and said operating mechanism to close the door; means to check the closing action of said closing means; and a rod mounted on the member carrying the operating mechanism and movable longitudinally to project beyond that member to engage the other member to prevent undesired closing of the door.

12. A device of the character described comprising a door or the like; a support therefor; means to close the door including a flexible element which extends from the door to the support and including a rotary element operatively connected with said flexible element; means to check the closing action of the closing means; and means including a longitudinally movable rod to engage said rotary member to stop undesired closing of the door.

13. A device of the character described comprising a door or the like; a support therefor; means to close the door including a spring and including a flexible element which extends from the door to the support; means to check the closing action of the closing means; and means to stop undesired closing of the door.

14. A device of the character described comprising a door or the like; a support therefor; means to close the door including a spring and including a flexible element which extends from the door to the support; means to check the closing action of the closing means; and means additional to said checking means to stop undesired closing of the door.

15. A device of the character described comprising a door or the like; a support therefor; means to close the door including a spring and including a flexible element which extends from the door to the support; means to check the closing action of the closing means; and means controlled by said checking means to stop undesired closing of the door.

16. A device of the character described comprising a door member; a supporting member therefor; a stationary casing embedded in one of said members; a piston fitting within, and cooperating with the casing; a spring within the casing and tending normally to actuate said piston to close the door, said piston forming an abutment for said spring; means within said casing and acting on said piston to check the closing action of said piston; a flexible element operatively connected to the other of said members; means operatively connecting said flexible element and said piston to close the door; and means to stop undesired closing of the door.

17. A device of the character described

1 comprising a door member; a supporting member therefor; a stationary casing embedded in one of said members; a piston fitting within, and cooperating with the casing; a spring within the casing and tending normally to actuate said piston to close the door, said piston forming an abutment for said spring; means within said casing and acting on said piston to check the closing action of said piston; a flexible element operatively connected to the other of said members; means operatively connecting said flexible element and said piston to close the door; and means controlled by said 15 checking means to stop undesired closing of the door.

18. A device of the character described comprising a door or the like; a support therefor; means to close the door; means to check the closing action of the closing means; and means to prevent undesired complete closing of the door, said means being movable to permit complete closing when desired.

19. A device of the character described 25 comprising a door or the like; a support therefor; means to close the door including a flexible element which extends from the door to the support; means to check the closing action of the closing means; and means to prevent undesired complete closing of the door, said means being operated by the closing means to permit complete closing when desired.

20. A device of the character described 35 comprising a door member or the like; a supporting member therefor; means to close the door including a flexible element which extends from the door member to the support member; means to check the closing 40 action of the closing means; and a rod projecting from one of said members to engage the other member to prevent undesired complete closing of the door, said rod being operated by the closing means to permit 45 complete closing when desired.

BENJAMIN S. BERNHARD.
